(57) **CLAIM**

The ornamental design for a monitor with stand, as shown and described.

DESCRIPTION

FIG. 1 is a perspective view of a monitor with stand showing our new design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view of the “monitor with stand,” showing parts of the “monitor with stand” in a first state of use.

FIG. 9 is another perspective view of the “monitor with stand,” showing parts of the “monitor with stand” in a second state of use; and,

FIG. 10 is another perspective view of the “monitor with stand,” showing parts of the “monitor with stand” in a third state of use.

The broken lines shown in the figures form no part of the claimed design, and the shaded lines in the figures show contour, not surface ornamentation.
